DISPLAY TREASURE CHEST

John E. Gillmore, Sr., Tampa, Fla., assignor to Crown Zellerbach Corporation, San Francisco, Calif., a corporation of Nevada

Application October 5, 1956, Serial No. 43,236

Term of patent 14 years

(Cl. D58—11)

FIG.1

Fig. 1 is a top view of a display treasure chest showing my new design;

Fig. 2 is a front view thereof;

Fig. 3 is an end view thereof;

Fig. 4 is a rear view thereof;

Fig. 5 is a perspective view; and

Fig. 6 is a perspective view shown with the lid in the open position.

I claim:

The ornamental design for a display treasure chest, as shown.
